UNITED STATES PATENT OFFICE.

HARRY GREENWOOD, OF BARNESBORO, PENNSYLVANIA.

FLAT-IRON HANDLE ATTACHMENT.

SPECIFICATION forming part of Letters Patent No. 703,699, dated July 1, 1902.

Application filed June 13, 1901. Serial No. 64,448. (No model.)

To all whom it may concern:

Be it known that I, HARRY GREENWOOD, a citizen of the United States, residing at Barnesboro, in the county of Cambria and State of Pennsylvania, have invented a new and useful Flat-Iron Handle Attachment, of which the following is a specification.

This invention relates to attachments for flat-irons having removable handles; and the purpose of the same is to provide simple and effective means for supporting the iron in such manner that its pressing-face will be held out of contact and clear of the surface of the adjacent supporting-base engaged by the attachments, the attachments being adjustable to adapt them for application to different sizes of flat-irons.

The invention consists in the construction and arrangement of the several parts, which will be more fully hereinafter described and claimed.

In the drawings, Figure 1 is a perspective view of a flat-iron of an approved form with my improvement attached thereto. Fig. 2 is an end view with the flat-iron turned on its side. Fig. 3 is a sectional detail of the handle, illustrating the manner of connecting the attachment.

Similar numerals of reference are employed to indicate corresponding parts in the several views.

The numeral 1 designates the usual flat-iron body, 2 the base of the handle portion, and 3 the usual attaching means for said portion. The base 2 of the handle portion is formed with elevated ends 4 and 5, to which the arcuate handle 6 is connected by screws 6^a in the usual manner. Between the ends of the arcuate handle 6 and the elevated ends 4 and 5 of the base 2 transverse recesses or grooves 8 are formed, in which the opposite parallel side members of wire loops 9 and 10 are adjustably supported and fixedly held when the ends of the handle 6 are secured to the ends 4 and 5, the said grooves being formed in the ends of the handle, and one member 11 and 12, respectively, of the loops 9 and 10 being extended in a straight plane and merging into an angularly-bent member 11^a and 12^a, respectively, of the two attachments and which are parallel with the adjacent side portions of the body of the iron

when applied in operative position. The members 11^a and 12^a, respectively, continue into inwardly-curved bends or extensions 13 and 14, which when the iron is turned side-wise, as shown by Fig. 2, will be in the same plane as the said members 11^a and 12^a, so as to rest flat on a supporting-base. The terminals 15 and 16 of the curved extensions 13 and 14 are curved or looped at an angle to the plane occupied by said extensions.

It will be seen that the loops 9 and 10 provide means for immovably holding the attachments after the securement of the handle 6 to the ends 4 and 5 is effected, and, furthermore, the said loops prevent the attachments from having a rotating or displacing movement. By loosening the screws 6^a the loops 9 and 10 can be adjusted transversely in relation to the handle ends and ends 4 and 5, as may be desired or found necessary in different applications of the improved device, and particularly when the attachments are applied to irons of different sizes.

The attachments will be preferably constructed of steel wire and may be plated or japanned or otherwise ornamented. The attachments are also capable of being independently adjusted to suit different forms of irons and to compensate for a variation in the center of gravity in accordance with a preponderance of material in different parts of the iron body.

What I claim as new is—

1. The combination with a flat-iron, of a pair of supporters therefor independently adjustable in relation thereto, each supporter having an upper elongated looped extremity, the members of said extremities being parallel and forming two opposite independent bearing portions adapted to be adjustably inserted between the handle ends and the body of said iron for preventing rotative movement of the supporters, one member of the looped extremity being continued into an outwardly-projecting straight extension merging into an angularly-bent portion which lies normally parallel with the side of the iron, said bent portion being continued into an inwardly-curved extension in the same plane as the bent portion for providing an extended rest for the iron.
2. The combination of a flat-iron having ele-

- vated portions at opposite extremities for attachment of a handle, a handle having a pair of transverse grooves in each end which are closed when the handle ends are secured to 5 said elevated portions, and a pair of supports having elongated loops engaging said grooves, the members of said loops being parallel and forming opposite bearing portions for preventing rotation thereof, one member of each loop 10 being projected in the form of a straight extension having an angularly-bent outer end extending normally parallel with the side of the iron, said extension having inwardly-curved extremities.
- 15 3. Means for supporting a flat-iron comprising two members, each member being independently adjustable in relation to the iron and provided with an upper elongated looped

extremity forming two opposite independent bearing portions adapted to be inserted between the handle ends and body of an iron, each member having an outwardly-projecting straight extension merging into an angularly-bent portion which normally lies parallel with the side of the iron, said bent portion having 25 an inwardly-curved extension in the same plane as the bent portion and forming an extended rest for the iron.

In testimony that I claim the foregoing as my own I have hereto affixed my signature in 30 the presence of two witnesses.

HARRY GREENWOOD.
